UNITED STATES PATENT OFFICE.

CLAYTON BELL, OF CENTRALIA, MISSOURI.

TELEGRAPH-TRANSMITTER.

1,173,702.

Specification of Letters Patent. Patented Feb. 29, 1916.

Application filed June 21, 1915. Serial No. 35,374.

To all whom it may concern:

Be it known that I, CLAYTON BELL, a citizen of the United States, residing at Centralia, in the county of Boone, State of Missouri, have invented certain new and useful Improvements in Telegraph-Transmitters; and I do hereby declare the following to be a full, clear, and exact description of the invention, such as will enable others skilled in the art to which it appertains to make and use the same.

This invention relates to a telegraph transmitter.

An object of the invention resides in the provision of a transmitter in which a circuit is made and broken a plurality of times upon one manual actuation of the dot lever to produce a series of dots used in the Morse code.

20 A further object of the invention resides in so constructing the device that it will be easily operated and will lessen the work of the operator.

With these and other objects in view, such as will appear as the description progresses, my invention comprises the combination and arrangement of parts as set forth in and falling within the scope of the appended claims.

30 Referring to the drawings: Figure 1 is a plan view of my device. Fig. 2 is a side elevation. Fig. 3 is a similar view looking at the opposite side of the device. Fig. 4 is an end elevation. Fig. 5 is a section on line 5-5 of Fig. 1. Fig. 6 is a section on line 6-6 of Fig. 1. Fig. 7 is a section on line 7-7 of Fig. 1. Fig. 8 is a fragmental detail of the compound lever.

Referring to the drawing wherein like parts are indicated by like characters throughout the several views:—In the embodiment of my invention shown in the drawing, I have provided a metallic base 1 which is supported by suitable rubber legs

45 2. Secured to the base 1 by means of screws 3 is a spring holder 4 to which is attached, by means of a bolt 5, a vibrator spring 6 to the end of which is attached a vibrator 7 which is in the form of a rod and has a weight 8 adjustably mounted thereon, which weight may be held in any of its adjusted positions by a set screw 9. The adjustment of this weight will determine the rate of vibration of the vibrator 7 and consequently 50 the frequency of the dots as will be later

described. A limiting post 10 for the vibrator is mounted on the base 1 adjacent the end of the vibrator and has an adjustable set screw 11 mounted therein on which set screw a lock nut 12 is mounted. The end 60 of the set screw 11 is provided with a point 13 of insulating material with which point the vibrator 7 contacts. The vibrator 7, the spring 6 and the holder 4 are in electrical communication with the base 1. Mounted 65 on the base 1 and insulated therefrom is a post 14 which has a set screw 15 adjustably mounted therein on which set screw is a lock nut 16 so that the set screw may be held in its adjusted positions. Secured to 70 the post 14 and insulated from the base 1 is a spring 17 having a contact point 18 on the end thereof which is adapted to engage the contact point 19 on the vibrator 7. The spring 17 includes a horizontally disposed 75 U-shaped portion and a vertically extending shank. The end of the screw 15 bears against the horizontal portion of the spring so that upon the adjustment of the screw the spring will be moved so that the contact point 18 will be adjusted with relation to the contact point 19 on the vibrator 7. Mounted on the base 1 is a binding post 20 in electrical communication with the base 80 and a second binding post 21 insulated from the base. Extending from the binding post 21 to the post 14 is a bus bar 22 which is insulated from the base. The binding posts 20 and 21 are adapted to receive the ends of the line wires in the usual manner. Thus 85 90 when the vibrator 7 is moved by the spring 6 so that the contacts 18 and 19 will engage each other a circuit will be set up from one line wire to the post 21, through the bus bar 22 to the post 14, through the springs 17 to 95 the contact 18, to the contact 19, through the vibrator 7 and spring 6 to the holder 4, through the base 1 to the binding post 20 and thence to the other line wire.

In order that the engagement of the contacts 18 and 19 may be controlled, I have provided a vibrator releasing lever 23 which is pivoted on a pintle 24, which pintle is mounted in a bearing 25 on the base and in an adjustable bearing 26 mounted on a 100 bracket 27. The lever 23 is provided with an arm 28 such as shown in Fig. 1 of the drawing which is adapted to engage the weight 8 upon the vibrator 7 and when in engagement with the said weight will pre- 105 110

vent the movement of the vibrator. This arm 28 is normally held in engagement with the weight 8 by a coil spring 29 which is attached to a set screw 30, which set screw is 5 adjustably mounted on a post 31 and held in its adjusted position by a lock nut 32. The movement of the lever 23 away from the vibrator is limited by a set screw 33 which is adapted to contact with the lever, 10 is adjustably mounted in a post 34 and held in its adjusted position by a lock nut 35. In order that this lever 23 may be actuated I have pivoted a second lever 36 on the pintle 24 which overlies the lever 23 and has a 15 stop member 37 secured to one face thereof, which stop member extends downwardly into contact with the adjacent face of the lever 23. Extending from this stop member 37 is a pin 38 which projects through a hole 20 in the lever 23 and has a nut 39 on the end thereof. Interposed between this nut 39 and the lever 23 is an expansion spring 40 which maintains the stop member 37, normally, in contact with the lever 23. Secured 25 to the other end of the lever 36 is a handle 41 and on the opposite face of the lever 36 is a knob 42, which handle and knob are made of suitable insulating material such as hard rubber.

30 Secured to the base 1 and insulated therefrom is a post 43 which has a contact member 44 adjustably mounted thereon, which contact member is adapted to engage an aligned contact 45 on the end of the lever 36. 35 Extending from the post 14 to the post 43 is a bus bar 46 which is insulated from the base 1. Secured to the post 43 and extending outwardly therefrom in slight spaced relation to the base 1 is a clip 47. Pivoted 40 to the base at 48 is a switch 49 which has a free end adapted to be forced between the clip 47 and the base 1 to complete the circuit when the device is not in use as will become apparent.

45 In using the device, when it is desired to send a series of dots it will only be necessary for the operator to engage the handle 41 and move the same in one direction at this time the stop member 37 on the lever 50 36, which lever, I will designate as the dash lever for the sake of convenience, will engage the vibrator releasing lever 23 and these levers 36 and 23 will be moved together against the tension of the spring 29 so that 55 the arm 28 will disengage the weight 8. Upon the disengagement of the weight 8 the vibrator 7 will move, the spring 6 having previously held the vibrator under tension. During this movement of the vibrator 60 7 the contact 19 thereon will intermittently engage the contact 18 on the spring 17 and the circuit previously described will be set up. It will only be necessary for the operator to maintain the pressure upon the handle 41 until the number of times the contacts

18 and 19 have engaged each other is sufficient to produce the required number of dots. When this has taken place the handle 41 may be released and the spring 29 will move the levers 23 and 36 into their initial 70 positions and the arm 28 into contact with the weight 8 so as to prevent the further vibration of the vibrator 7 and the consequent engagement of the contacts 18 and 19. It will thus be seen that to produce the required number of dots only one movement 75 of the operator's hand is necessary since, when the weight 8 is released, the vibrator 7 will be caused to move to intermittently close the line circuit. 80

When it is desired to send a dash it is only necessary for the operator to apply force to the knob 42 and move the same in a direction opposite to that in which the handle 41 is moved. At this time the dash lever 36 will 85 be swung toward the post 43 until the contact 45 thereon engages the contact 44 on the post. This movement of the lever 36 will take place against the action of the spring 40, which spring will be compressed 90 to allow the lever 36 to move independently of the lever 23. Force must be applied to the knob 42 for only such time as is necessary to produce one dash and when the knob is relieved of the pressure the spring 40 will 95 return the lever 36 to its initial position overlying the lever 23. When the contacts 44 and 45 engage, the circuit will pass from the post 21 through the bus bars 22 and 46 to the post 43, through the lever 36 to the base 1, through the base 1 to the binding post 20 through the line wire to the binding post 21. 100

When the instrument is not in use the circuit may be completed by moving the switch 49 so that it contacts with the clip 47 and thus the circuit will follow the last described circuit to the post 43 and thence through the switch to the base. 105

From the foregoing description it will be seen that I have provided a telegraph transmitter which is of such construction that a number of dots may be sent with but one manual operation. Specifically I have provided a vibrator which will close the circuit intermittently as many times as is desired by the operator to transmit dots. 110

While I have illustrated and described a particular embodiment of my invention, I have merely done so for the sake of convenience and I do not wish to be limited to that particular embodiment as it is obvious that numerous changes may be made within the details of construction thereof without in any way departing from the spirit 120 of the invention or exceeding the scope of the appended claims. 125

What I claim is:—

1. In a telegraph transmitter, the combination with a vibrator, of a lever having an 130

arm thereon adapted to engage the vibrator, a second lever mounted on the pivot of the first lever and movable relative thereto, means on the second lever for engaging the first lever to cause the movement of the first lever when the second lever is moved in one direction and resilient means for opposing the movement of the second lever independently of the first lever in the other direction.

2. In a telegraph transmitter, the combination with a vibrator, of a lever for controlling the movement of the same, a second lever mounted on the pivot of the first lever and movable independently thereof, the said levers being movable together to release the vibrator and means for limiting the independent movement of the second lever with relation to the first lever.

3. In a telegraph transmitter, the combination with a vibrator, of a lever for controlling the same, a second lever mounted on the pivot of the first lever and movable independently thereof, means on the second lever for engaging the first lever to cause the movement of the latter in one direction and resilient means for opposing the independent movement of the second lever, and resilient means adapted to coact with the first mentioned resilient means to move the levers together to arrest the movement of the vibrator.

In testimony whereof, I affix my signature, in the presence of two witnesses.

CLAYTON BELL.
